DESIGN FOR A DISPENSING CAP FOR CONTAINER

William Earl Hartman, Sr., Philadelphia, Pa., as-
signor to Pennsylvania Salt Manufacturing
Company, Philadelphia, Pa.

Application January 14, 1943, Serial No. 109,262

Term of patent 14 years

To all whom it may concern:

Be it known that I, William Earl Hartman, Sr., a citizen of the United States, residing at Philadelphia, county of Philadelphia, and State of Pennsylvania, have invented a new, original, and ornamental Design for a Dispensing Cap for Container, of which the following is a specification, reference being had to the accompanying drawing, forming a part thereof.

Fig. 1 is a top plan view of a dispensing cap for container showing my new design;

Fig. 2 is a side elevational view;

Fig. 3 and Fig. 4 are perspective views thereof.

I claim:

The ornamental design for a dispensing cap for container, substantially as shown.

WILLIAM EARL HARTMAN, SR.
